UNITED STATES PATENT OFFICE.

OLIVER P. McLENDON AND HARRY G. SMITH, OF KINGSVILLE, TEXAS; SAID SMITH
ASSIGNOR TO SAID McLENDON.

BALL-BEARING CAR SASH.

1,424,502.

Specification of Letters Patent. Patented Aug. 1, 1922.

Application filed May 17, 1921. Serial No. 470,445.

To all whom it may concern:

Be it known that we, OLIVER P. McLENDON and HARRY G. SMITH, citizens of the United States, residing at Kingsville, in the county of Kleberg and State of Texas, have invented certain new and useful Improvements in Ball-Bearing Car Sashes, of which the following is a specification.

Our invention relates to car sashes for railroad cars, street cars and the like, and has for its object to provide such a device with means to facilitate the raising and lowering of the window.

A further object of the invention is to provide a car sash with means which will prevent jamming at all times.

Another object of the invention is to provide concealed means for positively locking a car sash in any position desired.

Another object of the invention is to so locate the ball bearings and lock that they are entirely concealed, and can therefore be made of cheap material and will require no attention after being installed.

Other objects of the invention will appear from the following description when taken in connection with the accompanying drawing, in which—

Figure 1 is a fragmentary view of the sash frame and sash, a portion of the sash being cut away to show the construction.

Figure 2 is a vertical section through a portion of the sash frame.

Figure 3 is a horizontal section taken on line 3—3, Fig. 2.

Figure 4 is a horizontal section on line 4—4, Fig. 1; and

Figure 5 is a detail view.

Referring to the drawing in detail and in which similar numerals refer to similar parts throughout the several views; numeral 1 designates a car sash guided in the frame 2. Seated in recesses in each of the side stiles of the sash, at the top and bottom thereof are containers 3, secured in place by means of the screws 4.

Riveted to the base of each of the containers 3 is an arched leaf spring 5. As shown in the drawing, this spring is secured at one end to the base of the container and has its other end free to permit movement thereof. Suitably secured to the spring, at the top of the arch, is a ball bearing clip 6.

This clip is shown as carrying three balls 7, although a greater or less number may be used, as found desirable.

Secured in a recess in one side of the sash is a rack bar 8, which is adapted to cooperate with the locking member for the sash in a manner to be later described.

In the window frame 2 is located the locking mechanism, which consists of a pinion 9, which is mounted in bearings 10 in the U-shaped frame 11. This pinion is positioned so as to engage the teeth of the rack bar 8. The frame 11 is also provided with integral ears 12 to which is pivoted the locking pawl 13. To one end of pawl 13 is pivoted the plunger 14, provided on its end with the button 15. A coil spring 16 surrounds a portion of the plunger and engages the push button at one end and a portion of the window frame at the other end.

In the operation of raising or lowering the sash it is only necessary to press the button 15, against the pressure of spring 16. This movement is transmitted through plunger 14 to pawl 13, which is thereby raised from engagement with the teeth of the pinion 9. The sash, carrying the rack 8, may now be raised or lowered since the pinion is free to rotate on its axis.

The raising and lowering of the sash is greatly facilitated by the arrangement of the spring pressed bearings shown, since they not only reduce the usual friction but also prevent jamming of the sash against the frame.

It should also be noted that in the embodiment shown, the only exposed parts are the push button and sash lift (not shown). There are therefore no parts requiring polishing, etc., and furthermore, the working parts being concealed, can be made of the cheapest metal consistent with the strength required. Moreover, while we have shown the button and other locking means as located at the left of the sash, it will be understood that it may be placed at the right thereof if found desirable.

In accordance with the patent statutes, we have described what we now believe to be the best embodiment of the invention, but we do not wish to be understood thereby as limiting ourselves or the scope of the invention, as many changes and modifications may be

made without departing from the spirit of the invention, all such we aim to include in the scope of the appended claims.

What we claim as new and desire to secure 5 by Letters Patent is:

1. A car window sash provided with recesses adjacent the top and bottom thereof, bearings mounted in said recesses, each of said bearings including a clip, balls mounted 10 therein, and a spring pressing said clip and balls outwardly against the window frame in substantially the direction of the plane of the sash.
2. A car window sash provided with recesses adjacent the top and bottom thereof, 15 bearings mounted in said recesses, each of said bearings including a clip, balls mounted therein, and a spring pressing said clip and balls outwardly against the window frame 20 in substantially the direction of the plane of the sash, said spring being arch shaped and having one end free.
3. A car window sash provided with recesses adjacent the top and bottom thereof, 25 bearings mounted in said recesses, each of said bearings including a clip, balls mounted therein, and a spring pressing said clip and balls outwardly against the window frame in substantially the direction of the plane of 30 the sash, said spring being arch shaped and

being free at one end and attached to the sash at the other end.

4. A car window sash provided with recesses adjacent the top and bottom thereof, 35 bearings mounted in said recesses, each of said bearings including a clip, balls mounted therein, said clip being shaped to conform to the curvature of the balls, and a spring attached to said clip and pressing the clip and balls outwardly against the window 40 frame in substantially the direction of the plane of the sash, said spring being arch shaped and having one end free and the other end attached to the sash.

5. A car window sash and frame, including 45 a rack carried by the sash, a pinion mounted in the frame and engaging said rack, means entirely housed within the frame for engaging and locking said pinion against rotation, the sash being provided with recesses adjacent the top and bottom thereof, 50 bearings mounted in said recesses, each of said bearings including a clip, balls mounted therein, and a spring pressing said clip and balls outwardly against the window frame 55 in substantially the direction of the plane of the sash.

OLIVER P. MCLENDON.
HARRY G. SMITH.
